CORNICE HEADER FOR WINDOW DRAPES

Opal B. Haley, Amarillo, Tex.

Application July 22, 1957, Serial No. 47,043

Term of patent 14 years

(Cl. D13—4)

FIG. 1.

FIG. 2.

FIG. 3.

FIG. 4.

Fig. 1 is a front elevational view of a cornice header for window drapes showing my new design;

Fig. 2 is a top plan view thereof;

Fig. 3 is an end elevational view, the opposite end being substantially similar in appearance; and

Fig. 4 is a transverse sectional view thereof.

I claim:

The ornamental design for a cornice header for window drapes, substantially as shown and described.
